United States Patent Office

Des. 175,280
Patented Aug. 2, 1955

175,280

SPECTACLE FRONT

Raymond F. E. Stegeman, Greece, N. Y., assignor to
Bausch & Lomb Optical Company, Rochester, N. Y.,
a corporation of New York

Application January 20, 1955, Serial No. 34,094

Term of patent 7 years

(Cl. D57—1)

FIG. 1

FIG. 2

FIG. 3

Fig. 1 is a front elevational view of a spectacle front, showing my new design.

Fig. 2 is a top plan view thereof.

Fig. 3 is a front end perspective view thereof.

The essential features of my design are shown in full lines on the drawing.

I claim:

The ornamental design for a spectacle front, substantially as shown and described.
